UNITED STATES PATENT OFFICE

2,205,012

COAL MINING MACHINE

Joseph F. Joy, Claremont, N. H., assignor to
 Sullivan Machinery Company, a corporation of
 Massachusetts

Application May 27, 1936, Serial No. 82,153

6 Claims. (Cl. 262—30)

This invention relates to coal mining machines, and more particularly, but not exclusively, to improvements in coal mining machines of the flexibly fed, room and pillar, floor cutter type.

An object of this invention is to provide an improved coal mining machine. Another object is to provide an improved coal mining machine of the flexibly fed, floor cutter type having improved feeding and cutting mechanisms and improved means for driving the feeding and cutting mechanisms. A further object is to provide an improved coal mining machine of the flexibly fed, floor cutter type having an improved arrangement of the feeding and controlling drums and an improved guiding arrangement for the flexible feeding and controlling cables whereby the machine may be fed and controlled in an improved manner. Still another object is to provide an improved coal mining machine of the flexibly fed, floor cutter type having an extremely compact arrangement of parts whereby the overall dimensions of the machine are maintained at a minimum. A still further object is to provide an improved coal mining machine of the flexibly fed, floor cutter type having improved supporting means providing plane supporting surfaces at the top and bottom of the machine whereby the machine may be operated either as an under cutter or an overcutter simply by inverting the machine. Still another object is to provide in a machine of the above character an improved guiding arrangement for the flexible feeding and controlling cables whereby the machine may be fed in either of opposite directions across the coal face while the machine is supported on either supporting surface thereof. Yet another object of this invention is to provide an improved driving means for the feeding and controlling drums embodying improved means for releasing the drums from their driving means. Still another object is to provide a relatively inexpensive and compact mining machine, which is comparatively simple in construction and light in weight. Other objects and advantages of the improved mining machine will be clearly apparent to those skilled in the art.

In the accompanying drawings there is shown for purposes of illustration one form which the invention may assume in practice.

50 In these drawings—

Fig. 1 is a plan view of the illustrative embodiment of the improved mining machine showing the cutter bar in under cutting position, the top plate being partially broken away to facilitate illustration.

Fig. 2 is a side elevational view of the machine shown in Fig. 1.

Fig. 3 is a side elevational view, on a reduced scale, showing the machine in its inverted overcutting position.

Fig. 4 is a rear end elevational view of the machine shown in Figs. 1 and 2.

Fig. 5 is an enlarged view in longitudinal vertical section taken substantially on line 5—5 of Figs. 1 and 7.

Fig. 6 is an enlarged detail horizontal sectional view taken substantially on line 6—6 of Fig. 5.

Fig. 7 is an enlarged view in horizontal section taken substantially one line 7—7 of Figs. 2 and 5.

Fig. 8 is a view in longitudinal vertical section taken substantially on line 8—8 of Fig. 7.

Fig. 9 is a view in longitudinal vertical section taken substantially on line 9—9 of Fig. 7.

Fig. 10 is a detail sectional view taken substantially on line 10—10 of Fig. 9.

Fig. 11 is a horizontal sectional view taken substantially one line 11—11 of Fig. 2 showing the cutter bar support and bottom plate structure.

Fig. 12 is an electrical diagram showing the motor reversing switches and the associated interlock means.

Fig. 13 is a diagrammatic view showing the machine cutting from left to right with the machine in undercutting position.

Fig. 14 is a diagrammatic side elevational view of the machine in the position shown in Fig. 13.

Fig. 15 is a diagrammatic plan view showing the machine cutting from left to right with the machine in overcutting position.

Fig. 16 is a diagrammatic plan view showing the machine cutting from right to left.

Fig. 17 is a side elevational view of the machine in the position shown in Fig. 16.

In this illustrative embodiment of the invention there is shown a coal mining machine of the flexibly fed, room and pillar, floor cutter type, although it will be evident that various features of the invention may be incorporated in coal mining machines of various other types.

The coal mining machine as disclosed herein comprises an invertible machine frame 1 adapted to rest upon and slide in any direction over the mine floor and presenting parallel plane top and bottom surfaces 2 and 3 upon which the machine is adapted to be selectively supported, that is when the machine is being operated as an undercutter or inverted and operated as an overcutter. The machine frame 1 includes a front

feed and cutter frame section 4, a rear motor frame section 5, a detachable top skid plate 6 providing the plane supporting surface 2, and a detachable bottom skid plate 7 providing the bottom supporting surface 3, the frame sections 4 and 5 and the top and bottom plates being rigidly united to form a compact unitary structure. Projecting forwardly horizontally from the machine frame is an elongated, horizontal, plane cutter bar 8 having mounted on its margin for circulation thereabout, an endless cutter chain 9. The cutter bar is supported by and rigidly fixed at its inner end to a hanger frame 10 detachably secured as by screws 11 to the feed and cutter frame 4, this hanger frame having a circular portion 12 formed with a bore 13 receiving a cylindrical bearing support 14 integral with a detachable cover plate 15 in turn secured as by screws 16 to the feed and cutter frame 4. Secured as by welding to the bottom plate 7 and interposed between the bottom plate and the cutter bar 8 is a supporting plate 17, and this plate 17 and the cutter bar and bar hanger are rigidly secured together as by screws 18.

Now referring to the driving mechanism for the cutter chain, it will be noted that arranged within the motor frame section 5 is a motor 19, herein preferably of the reversible electric type, having its power shaft 20 horizontally disposed and extending longitudinally of the machine at substantially the longitudinal center of the latter. Keyed to the front end of the motor power shaft 20 is a bevel gear 21 having its hub 22 journaled in a ball bearing 23 suitably supported within the feed and cutter frame. The bevel gear 21 meshes with a large horizontal bevel gear 24 having its hub 25 journaled in a ball bearing 26 supported within the cylindrical bearing support 14, and a ball bearing 27 supported within a cylindrical bearing support 28 formed integral with the detachable cover plate 15 and projecting inwardly therefrom in the manner shown in Fig. 5. Journaled within the bearing sleeves 29 supported within the hub of the bevel gear 24 is a vertical shaft 30 having keyed thereto at its lower end, as viewed in Fig. 5, a chain sprocket 31 which engages and drives the endless cutter chain 9. As illustrated, secured by screws 32 to the bearing support 14 is an annular retaining plate 33 for retaining the ball bearing 27 in position within the bearing support, and this plate 33 carries a packing 34 embracing the hub of the chain sprocket 31 to provide a dust and oil seal. The chain sprocket 31 is arranged in a horizontal chamber 35 extending transversely of the machine between the cutter and feed frame and the bottom plate 7, and the inner end of the cutter chain moves through this chamber, the chamber being open at the opposite sides of the machine frame so that the cuttings brought back from the kerf by the cutter chain are discharged through the sides of the chamber. The bottom skid plate 7 is preferably cut away at the bottom of the cutter chain sprocket chamber, in the manner shown in Fig. 11, thereby to facilitate the discharge of cuttings from the chamber as the machine moves laterally over the mine floor during the cutting operation.

The means for connecting the cutter chain sprocket drive shaft 30 to the bevel gear 24, as shown in Figs. 5 and 6, comprises an expandable toothed clutch 36 comprising several radially located, interlocking clutch members 37 guided within radial slots 38 formed in the shaft 30 and adapted to project within sockets 39 formed

in the hub 25 of the bevel gear. Arranged coaxially with the shaft 30 and slidably axially within a bore 40 therein is an operating plunger or rod 41 having a conical inner end 42 adapted to engage the clutch members 37 for spreading the latter apart. The operating rod 41 is movable axially by means of a shipper yoke 43 engageable with a collar 44 at the upper end of the rod, as shown in Fig. 5. The shipper yoke 43 is fixed to a transverse operating shaft 45 having an operating lever 46 conveniently located on the exterior of the machine frame. It will thus be seen that when the operating rod 41 is in the position shown in Fig. 5 the interlocking plungers 37 are moved into interlocking relation with the sockets 39 in the bevel gear hub so that the shaft 30 is locked to the bevel gear for rotation therewith, and as a result when the clutch is so connected the cutter chain sprocket 31 is driven from the motor 19 through the bevel gearing 21, 24 to effect rapid circulation of the cutter chain about the margin of the cutter bar. When the operating rod 41 is raised from its position shown in Fig. 5 the interlocking plungers are permitted to move inwardly into their released position, thereby to release the drive shaft 30 from the bevel gear 24, and, as a result, the cutter chain is disconnected from its drive.

The feeding mechanism for the machine comprises a plate 48 secured by screws 49 to the bevel gear 24 and having a hub 50 keyed to a worm 51, this worm herein arranged with its axis coincident with the axis of the bevel gear and shaft and driven by the bevel gear. This worm 51 meshes with a worm wheel 52 keyed to a horizontal shaft 53, herein extending across the machine above the bevel gear 24 and journaled at its opposite ends within ball bearings 54 and 55, the former being suitably supported within a bearing bracket 56, preferably formed integral with the cutter and feed frame, while the latter is supported within a detachable bearing bracket 57 secured as by screws 58 to the cutter and feed frame 4. Formed integral with this shaft 53 is a spur gear 59 meshing with a spur gear 60 keyed to a shaft 61 herein horizontally disposed and extending transversely of the machine frame at the rear of the shaft 53. Also keyed to the shaft 61 is a bearing hub 62 journaled in a ball bearing 63 supported within a detachable bearing bracket 64 secured as by screws 65 to the feed and cutter frame 4. Fixed to and driven by the shaft 61 is a spur gear 66 meshing, as shown most clearly in Fig. 9, with the teeth of an internal gear 67 formed on a feed drum 68. This drum 68 is journaled for rotation about a horizontal axis extending transversely of the machine on bearing sleeves 69 supported by a shaft 70, herein secured as by welding within a bore 71 formed within a supporting boss 72 integral with a swingable frame 73. This frame is journaled at 74 on a horizontal transversely extending shaft 75, herein secured as by welding within a bore 76 formed within a boss 77 integral with the feed and cutter frame 4. The frame 73 is provided with an operating lever 78 projecting rearwardly along the side of the machine frame and having a grasping handle 79. Suitable releasable locking means is provided for locking the lever in its different adjusted positions. The operator, by swinging the lever 78, may rock the frame 73 about its pivotal mounting on the shaft 75 to move the internal gear 67 on the drum into and out of meshing engagement with the teeth of the spur gear 66. Formed in-

tegral with the frame 73 is a stop lug 80 engageable with spaced stops 81 rigidly secured to the adjacent side of the feed and cutter frame 4, and this stop lug 80 limits the amount of swinging movement of the frame 73. Keyed to the shaft 53 at the opposite side of the machine from the spur gear 59 is a relatively large spur gear 82 meshing with a spur gear 83 keyed to the hub of a controlling drum 84, the latter arranged at the opposite side of the machine from the feed drum 68 as shown in Fig. 1. The drum 84 is journaled for rotation on a horizontal axis extending transversely of the machine on ball bearings 85 supported by a shaft 86 secured as by welding 15 to a swingable frame 87 pivotally mounted at 88 on a horizontal transverse shaft 89 rigidly secured within the adjacent side of the feed and cutter frame. The frame 87 is formed with a lever 90 projecting rearwardly along the side of the machine frame and having an operating handle 91 for swinging the frame about its pivot to move the spur gear 83 into and out of meshing engagement with the spur gear 82. Suitable releasable locking means is provided for locking 25 the lever in its different adjusted positions. This swinging frame is likewise provided with a stop lug 92 engageable with spaced stops 93 rigidly fixed to the adjacent side of the feed and cutter frame 4, and these stops limit the amount which 30 the frame 87 can be swung. It will thus be seen that the drums may be quickly thrown into engagement with or disconnected from their drives simply by swinging the frame levers to swing the drum-carrying frames about their pivotal 35 mountings.

The spur gearing 59, 60, 66, 67 constitutes low speed driving means for the feeding drum 68, while the spur gears 82, 83 constitute high speed driving gearing for the controlling drum 84. A 40 friction brake is provided for retarding rotation of the controlling drum 84 when the latter is disconnected from its driving gear 82 comprising, housed within the drum, a series of brake discs 94 keyed to the shaft 86 and interleaved with a 45 series of brake discs 95 keyed to the controlling drum 84. Mounted centrally within the shaft 86 is a screw 96 having threaded thereon an adjusting nut 97 having an operating handle 98. This nut is provided with a collar 99 engageable 50 with the outer surface of a pressure plate 100 engageable with the inner race of the adjacent ball bearing 85. The opposite side of the inner ball bearing race engages a brake applying plate 101. When the nut 97 is screwed inwardly along the 55 screw 96, the pressure plate 100, the inner race of the ball bearing and the plate 101 are moved inwardly frictionally to connect the braking plates together, thereby to frictionally brake drum rotation. By regulating the application of 60 the braking pressure the controlling drum may rotate in unwinding direction, that is, a direction to pay out the controlling cable, under various degrees of frictional resistance, for a purpose to be later described.

Means is provided for frictionally resisting rotation of the feed drum 68 so that when the latter is suddenly disconnected from its drive, undue spinning thereof and a resultant undesirable unwinding of the feed cable are prevented. This 65 spinning brake comprises a braking plunger 103 mounted in a sleeve 104 guided within a bore 105 formed within a cylindrical guide 106 secured within the swinging frame 73. Engaging a flange 107 on the sleeve 104 and the inner wall 70 of the guide bore is a coil spring 108 for con-

stantly yieldingly urging the braking plunger into frictional engagement with the adjacent plane surface 109 of the feed drum.

Wound on the feeding drum 68 is a flexible feeding cable 110, while wound on the controlling drum 84 is a flexible controlling cable 111, and the improved guiding means for these cables for guiding the latter during the various operations of the machine comprises sets of coaxial horizontal guide sheaves 112, 113 and 114, 115 suitably journaled on the machine frame at the opposite rear corners thereof, while arranged near the longitudinal vertical center of the machine is a set of coaxial horizontal guide sheaves 116, 117, the guide sheaves of each set respectively 16 journaled at the top and bottom of the motor frame section. Arranged at opposite sides of the machine are sets of vertical guide sheaves 118, 119 and 120, 121 herein journaled at the opposite sides of the machine frame on horizontal axes 20 extending transversely of the machine. Arranged at the opposite front corners of the machine are guide sheaves 122 and 123 journaled on vertical axes on projecting brackets 124 formed integral with the feed and cutter frame. 25

The electrical control means for the motor 19 for effecting operation of the latter selectively in opposite directions, thereby to drive the cutter chain in either of opposite directions, comprises, as shown most clearly in Fig. 4, a pair of reversing 30 switches 125 and 126 arranged within the rearward portion of the motor frame and having vertically swingable operating levers 127 and 128 respectively. These switches are so connected in the circuit of the motor that when one is "on" 35 and the other is "off" the motor runs in one direction, and when the second switch is "on" and the first switch is "off" the motor runs in the reverse direction. An interlock is provided between the two switches for preventing simultaneous 40 movement of the switch levers into their "on" position comprising a transverse interlocking bar 129 guided for transverse sliding movement within guides 130 secured to the rear side of the motor frame, and this bar has a centrally located 45 circular portion 131 surrounding a detachable end plate 132 of the motor frame, the circular portion having sufficient clearance with respect to the plate 132 so as to permit sliding movement of the interlocking bar back and forth in its 50 guides, while engagement of the circular portion 131 with the plate 132 limits the sliding movement of the interlocking bar in either direction. When the interlocking bar is slid in one direction, one switch lever is released therefrom while the 55 other lever is locked in its off position by the end of the bar extending above the lever. Of course, when the bar is slid into its opposite position the other switch lever is locked, while the switch lever first mentioned is released so that 60 the motor may be reversed. As shown diagrammatically in Fig. 12, the power conductor line is indicated at 133, the shunt field of the motor 19 at 134 and the series field at 135. When the switch 125 is closed and the switch 126 is open, 65 power may flow from the line 133 past the switch 125 and through a conductor 136 to the motor 19, while the opposite side of the motor is connected through conductors 137 and 138 past the switch 125 and through a conductor 139 to the 70 return conductor 140. When the switch 126 is closed and the switch 125 is open, power may flow from the conductor 133 through a conductor 141 past the switch 126 and through the conductor 137 to the motor 19, and the opposite side of the 75

motor is connected through the conductor 136 and a conductor 142 past the switch 126 and through the conductor 139 to the return line 140. It will thus be seen that the motor may 5 be operated selectively in opposite directions and by the provision of the interlock only one switch can be operated at a time.

When it is desired to sump the cutter bar beneath the coal at the right hand rib with the 10 cutter bar in undercutting position, the feed cable 110 may be extended from the bottom of the feed drum 68 to a suitable anchor jack located at the right hand rib, and as the drum 68 is rotated to wind in the feeding cable the machine is moved 15 in an endwise direction to sump the cutter bar beneath the coal. When it is desired to sump the cutter bar beneath the coal at the left hand rib, the feeding cable is extended from the feeding 20 drum beneath the guide sheave 119 and around the guide sheaves 114, 116, 112 and forwardly along the receding side of the machine to an anchor jack located near the left hand rib, and as the feed drum is rotated to wind in the cable the machine is moved in an endwise direction 25 to sump the cutter bar beneath the coal. The feed drum is also utilized to effect sumping of the cutter bar beneath the coal when the machine is inverted with the cutter bar in overcutting position, it being possible to extend the 30 feeding cable from the feeding drum in various manners about the various guide sheaves so that movement of the machine may be effected to effect sumping.

When the machine is operating from right to 35 left with the cutter bar in undercutting position, as viewed in Figs. 1 and 2, the feeding cable 110 is extended rearwardly from the top of the feed drum 68 around the guide sheave 119, then forwardly around the front guide sheave 122 at the 40 front receding corner of the feed frame and then transversely across the front end of the machine past the front guide sheave 123 and laterally from the machine to a suitable anchor jack located near the coal face at the left hand rib. To permit the feed cable to be extended transversely 45 across the front end of the machine frame between the front sheaves 122, 123, the hanger frame is cut away at 143 to provide a horizontal bottom ledge 144 underlying the cable, and this 50 ledge inhibits conflict of the cable with the cutter chain in the event of slackening of the feed cable. The controlling cable 111 is at that time extended rearwardly from the top of the controlling drum 84 around the lower guide sheave 55 121 at the advancing side of the machine, around the horizontal bottom guide sheaves 112, 116 and laterally from the receding side of the machine to an anchor jack located at the right hand rib. When the feeding and controlling cables 110, 111 60 are so arranged and the drums are connected to their driving means the feed drum 68 is rotated to wind in the feeding cable 110 to effect movement of the machine laterally across the coal face toward the left hand rib. During the transverse cutting operation the controlling drum 84 65 is disconnected from its drive and pays out the controlling cable 111 under the control of the friction brake to control the angular position of the machine with respect to the coal face. When 70 the transverse cutting operation is completed the machine is angled with respect to the left hand rib, and thereafter the feeding cable is arranged with respect to the feed drum and connected to 75 an anchor jack located at the rear end of the

machine so that the machine is moved rearwardly with respect to the coal face to withdraw the cutter bar from beneath the coal.

When the machine is operating from left to right with the cutter bar in undercutting position as viewed in Figs. 13 and 14, the feed cable 110 is extended from the bottom of the feed drum 68 around the guide sheave 119 and then forwardly, beneath the feed drum, along the advancing side of the machine to the front guide sheave 122, the cable being extended around the guide sheave 122 and laterally from the machine to an anchor jack located at the right hand rib. The controlling cable 111 is at that time extended from the bottom of the controlling drum 84, 15 around guide sheave 121, around the guide sheaves 112, 116 and then laterally from the rear end of the machine to an anchor jack located at the left hand rib. As the feed drum 68 is rotated to wind in the feed cable 110, the machine is fed laterally across the coal face, the controlling drum 84, which is disconnected from its drive, paying out the controlling cable 111 under the frictional control of the friction brake at that time. Upon completion of the transverse cutting operation, the cutter bar is angled with respect to the right hand rib and thereafter the machine is withdrawn from the face to complete the cut. 20

When the machine is cutting from left to right with the cutter bar in overcutting position, as viewed in Figs. 3 and 15, the feed cable 110 is extended from the feed drum 68 around the guide sheave 119 then forwardly beneath the feed drum, along the advancing side of the machine, around the front guide sheave 122, then transversely across the forward end of the machine frame past the front guide sheave 123 and laterally from the machine to an anchor jack located at the right hand rib, while the controlling cable 111 is extended from the bottom of the controlling drum 84 around the guide sheave 120 40 and around the guide sheaves 113, 117 and 115, and laterally from the receding side of the machine to an anchor jack located at the left hand rib. In all the various arrangements of the feeding and controlling cables with respect to the feeding and controlling drums and the various guide sheaves, the machine is moved in an endwise direction to sump in the cutter bar beneath the coal at one rib, then fed transversely across 50 the coal face, angled with respect to the opposite rib and thereafter withdrawn from the coal face, all in a manner well understood by those skilled in the art. 45

As a result of this invention it will be noted 55 that an improved coal mining machine of the invertible type is provided adapted to operate either as an overcutter or an undercutter and having an improved arrangement of the feeding and controlling drums and the guiding means for 60 the feeding and controlling cables, whereby the machine may be fed during either undercutting or overcutting in an improved manner. It will further be noted that an improved mining machine is provided of relatively compact and rugged 65 construction having an extremely simple arrangement of parts whereby the machine is rendered extremely inexpensive in cost and relatively light in weight. Other uses and advantages of the improved mining machine will be clearly apparent to those skilled in the art. 70

While there is in this application specifically described one form which the invention may assume in practice, it will be understood that this form of the same is shown for purposes of 75

illustration and that the invention may be modified and embodied in various other forms without departing from its spirit or the scope of the appended claims.

5 What I claim as new and desire to secure by Letters Patent is:

1. In a mining machine, a machine frame adapted to rest upon and slide in any direction over the mine floor and having top and bottom surfaces, a motor on said frame having its power shaft horizontally disposed and extending longitudinally of the machine, a horizontal plane kerf cutter projecting horizontally from the forward end of said frame adjacent one of said frame surfaces, the bottom of said motor lying in horizontal planes below the top plane surface of said kerf cutter, said kerf cutter having its driving element disposed on a vertical axis disposed a substantial distance in advance of said motor, a bevel pinion fixed to the forward end of the motor power shaft, a bevel gear meshing with said bevel pinion and arranged coaxially with and connectible to said kerf cutter driving element, and feeding means for the machine driven by the forward end of the motor power shaft including a feed driving element coaxial with said bevel gear.

2. In a mining machine, a machine frame adapted to rest upon and slide in any direction over the mine floor and having top and bottom surfaces, a motor on said frame having its power shaft horizontally disposed and extending longitudinally of the machine, a horizontal plane kerf cutter projecting horizontally from the forward end of said frame adjacent one of said frame surfaces, the bottom of said motor lying in horizontal planes below the top plane surface of said kerf cutter, said kerf cutter having its driving element disposed on a vertical axis disposed a substantial distance in advance of said motor, a bevel pinion fixed to the forward end of the motor power shaft, a bevel gear meshing with said bevel pinion and arranged coaxially with and connectible to said kerf cutter driving element, and feeding means for the machine driven by the forward end of the motor power shaft, said feeding means including a worm connected to and driven by said bevel gear, a worm wheel meshing with said worm, a cable winding drum, and driving connections between said worm wheel and said drum.

3. In a mining machine, a machine frame adapted to rest upon and slide in any direction over the mine floor and having top and bottom surfaces, a motor on said frame having its power shaft horizontally disposed and extending longitudinally of the machine, a horizontal plane kerf cutter projecting horizontally from the forward end of said frame adjacent one of said frame surfaces, the bottom of said motor lying in horizontal planes below the top plane surface of said kerf cutter, said kerf cutter having its driving element disposed on a vertical axis disposed a substantial distance in advance of said motor, a bevel pinion fixed to the forward end of the motor power shaft, a bevel gear meshing with said bevel pinion and arranged coaxially with and connectible to said kerf cutter driving element, and feeding means for the machine driven by the forward end of the motor power shaft, said feeding means including relatively rotatable cable winding drums, a worm connected to and driven by said bevel gear, a worm wheel mesh-

ing with said worm, and driving connections between said worm wheel and said drums.

4. In a mining machine, a machine frame adapted to rest upon and slide in any direction over the mine floor and having top and bottom surfaces, a motor carried on said frame at the rearward end thereof, said motor having its power shaft horizontally disposed and extending longitudinally of the machine, a horizontal plane kerf cutter projecting forwardly from said frame adjacent one of said frame surfaces, the bottom of said motor lying in horizontal planes below the top plane surface of said kerf cutter, said kerf cutter having its rearward portion disposed in advance of said motor, driving connections between the forward end of said motor and said kerf cutter, and feeding means for the machine driven from the forward end of the motor power shaft including a cable winding drum, a motor driven driving member mounted at the forward end of the machine frame for rotation about a vertical axis, a worm coaxial with and driven by said driving member, a worm wheel meshing with said worm, and driving connections between said worm and said drum.

5. In a mining machine, a machine frame adapted to rest upon and slide in any direction over the mine floor and having top and bottom surfaces, a motor carried on said frame at the rearward end thereof, said motor having its power shaft horizontally disposed and extending longitudinally of the machine, a horizontal plane kerf cutter projecting forwardly from said frame adjacent one of said frame surfaces, the bottom of said motor lying in horizontal planes below the top plane surface of said kerf cutter, said kerf cutter having its rearward portion disposed in advance of said motor, driving connections between the forward end of said motor and said kerf cutter, and feeding means for the machine driven from the forward end of the motor power shaft including relatively rotatable cable winding drums, a motor driven driving member journaled on the forward end of said machine frame for rotation about a vertical axis, a worm coaxial with and driven by said driving member, a worm wheel meshing with said worm, and driving connections between said worm wheel and said drums.

6. In a mining machine, a machine frame adapted to rest upon and slide in any direction over the mine floor and having top and bottom surfaces, a motor carried by said frame at the rearward end thereof, said motor having its power shaft horizontally disposed and extending longitudinally of the machine, a horizontal plane kerf cutter projecting forwardly from said frame adjacent one of said frame surfaces, the bottom of said motor lying in horizontal planes below the top plane surface of said kerf cutter, the rearward portion of said kerf cutter disposed in advance of said motor, driving connections between the forward end of the motor power shaft and said kerf cutter including a kerf cutter driving element journaled at the forward end of the machine frame for rotation about a vertical axis, and means for feeding the machine including a cable winding drum, a gear driven from the forward end of the motor power shaft and arranged coaxially with said kerf cutter driving element, a gear meshing with said gear, and driving connections between said last mentioned gear and said drum.

JOSEPH F. JOY.
